UNITED STATES PATENT OFFICE.

HENRY JONES, OF CROSS KEYS, NEAR NEWPORT, ENGLAND.

OIL-CAN.

1,165,511.

Specification of Letters Patent.

Patented Dec. 28, 1915.

Application filed November 2, 1914. Serial No. 869,828.

To all whom it may concern:

Be it known that I, HENRY JONES, a subject of the King of Great Britain, residing at Cross Keys, near Newport, in the county 5 of Monmouth, England, have invented certain new and useful Improvements in or Relating to Oil-Cans, of which the following is a specification.

This invention relates to oil-cans of the 10 kind that are combined with lamps to obviate the necessity of carrying a separate lamp or light at night, or into dark places, when oiling machinery, and whereby the 15 manipulating of the oil-can, as well as the carrying of the light or lamp, may be performed by one hand.

The chief object of the invention is to 20 provide such a combined oil-can and lamp wherein the latter is so arranged relatively 25 to the spout of the oil-can that the light shall be used to the best advantage, and further to permit of lamps being applied to existing as well as new oil-cans.

According to the invention the lamp comprises a tube or cylindrical member adapted 25 to be fitted to the spout of the oil-can, and containing a dry battery or other suitable light generating medium. The front end of 30 said tube or cylindrical member is fitted with a lens or reflector to direct the light from the lamp to the outlet end of the spout or to any point where it is desired to feed the oil. The lamp may be made a sliding fit on the spout and may be provided with means 35 for fixing it in position thereon. Suitable contacts may also be provided for making and breaking the electric circuit of the lamp.

In order that the invention may be clearly understood and readily carried into effect 40 the same will be more fully described with reference to the accompanying drawing, in which:—

Figure 1 is an elevation of an oil-can with a lamp applied according to one arrangement. Fig. 2 is a similar view to Fig. 1 showing a modification.

a is the lamp casing which is preferably made of cylindrical form with clips a' adapted to engage the spout b' of the oil can b as shown in Fig. 1. The placing of the lamp on to the spout may serve to complete the circuit and for this purpose a press or push switch c on the lamp may engage the spout or a protuberance or projection b' on the spout, the sliding or turning of the

lamp in to position serving to operate the switch to complete the lamp circuit and light the lamp.

In the arrangement shown in Fig. 2, the lamp a' is made to fit over the spout b', while the lamp filaments may be arranged in one or more small bulbs d with suitable reflectors for directing the light to the outer end of the spout b'. In this case also the placing of the lamp into position may serve 60 to effect the lighting, while to allow for the usual taper form of the spout and to hold the lamp firmly thereon, the opening in the tube or casing through which the spout passes may have a spring e or other resilient 65 means capable of binding against the spout to hold the lamp in any desired position thereon.

The attachment or tube containing the battery and lamp will in all cases be provided with a removable lid or cover whereby the lamp may be removed or the dry battery recharged, which closed or sealed tube also permits of the lamp being used with safety in places charged with gas. Further, 75 the lamp is such that when not required to be used with the oil-can it is capable of being carried in the pocket or in a suitable case. In this connection also the attachment means may serve as a handle whereby the 80 lamp can be carried and used independently of the oil-can.

What I claim and desire to secure by Letters Patent of the United States is:—

1. The combination with an oil can having an extended and tapered spout, of a lamp, means on said lamp for attaching the lamp to the spout and means for automatically lighting the lamp immediately it is placed in position.

2. The combination with an oil can having a spout, of a cylindrical lamp, means on said lamp for fitting around the spout, and means adapted to engage said spout for lighting the lamp.

3. The combination with an oil can having a spout, of a lamp having an aperture therethrough, and a resilient spout-engaging element positioned within said aperture.

In testimony whereof I affix my signature 105 in presence of two witnesses:

HENRY JONES.
